(57) **CLAIM**

The ornamental design for a headcap housing, as shown and described.

DESCRIPTION

FIG. 1 is a front perspective view of a headcap housing showing our new design;

FIG. 2 is a rear perspective view of the headcap housing shown in FIG. 1;

FIG. 3 is a front elevational view of the headcap housing shown in FIG. 1;

FIG. 4 is a rear elevational view of the headcap housing shown in FIG. 1;

FIG. 5 is a left-side elevational view of the headcap housing shown in FIG. 1;

FIG. 6 is a right-side elevational view of the headcap housing shown in FIG. 1;

FIG. 7 is a top plan view of the headcap housing shown in FIG. 1; and,

FIG. 8 is a bottom plan view of the headcap housing shown in FIG. 1.

The broken lines immediately adjacent the shaded areas represent the bounds of the claimed design while all other broken lines are directed to environment and are for illustrative purposes only; the broken lines form no part of the claimed design.

1 Claim, 8 Drawing Sheets
